(57) **CLAIM**

The ornamental design for a bodysuit, as shown and described.

DESCRIPTION

FIG. 1 is a front perspective view of a first embodiment of a bodysuit;

FIG. 2 is a front elevation view of FIG. 1;

FIG. 3 is a rear elevation view of FIG. 1;

FIG. 4 is a left elevation view of FIG. 1;

FIG. 5 is a right elevation view of FIG. 1;

FIG. 6 is a top plan view of FIG. 1;

FIG. 7 is a bottom plan view of FIG. 1;

FIG. 8 is a front perspective view of a second embodiment of the bodysuit;

FIG. 9 is a front elevation view of FIG. 8;

FIG. 10 is a rear elevation view of FIG. 8;

FIG. 11 is a left elevation view of FIG. 8, the right elevation view being a mirror image of FIG. 11;

FIG. 12 is a top plan view of FIG. 8; and,

FIG. 13 is a bottom plan view of FIG. 8.

The evenly sized broken lines shown in the drawings depict portions of the bodysuit that form no part of the claimed design, while the unevenly sized (dash-dot-dash) broken lines represent the bounds of the claimed design.
